(57) **CLAIM**

The ornamental design for a combined container and field
responsive material, as shown and described.

DESCRIPTION

FIG. 1 is a top plan view thereof;

FIG. 2 is a bottom plan view thereof;

FIG. 3 is a left side elevational view thereof;

FIG. 4 is a right side elevational view thereof;

FIG. 5 is a front elevational view thereof; and,

FIG. 6 is a back elevational view thereof.

The fragmentary broken line representations of the hands
and magnet shown in FIG. 5 and FIG. 6 are for illustrative
purposes only and form no part of the claimed design.

1 Claim, 4 Drawing Sheets

FIG. 3.

FIG. 4.
